UNITED STATES PATENT OFFICE.

WALTER E. BENNETT, OF CARBONDALE, PENNSYLVANIA, ASSIGNOR TO THE HENDRICK MANUFACTURING COMPANY, LIMITED, OF SAME PLACE.

ELEVATOR SAFETY DEVICE.

SPECIFICATION forming part of Letters Patent No. 604,957, dated May 31, 1898.

Application filed May 20, 1897. Serial No. 637,872. (No model.)

To all whom it may concern:

Be it known that I, WALTER E. BENNETT, a citizen of the United States, residing at Carbondale, in the county of Lackawanna and 5 State of Pennsylvania, have invented a certain new and useful Improvement in Elevator Safety Devices, of which the following is a specification.

This invention contemplates the provision 10 of mechanism whereby the opening of the door of an elevator-hoistway will securely lock the starting and stopping rope of the elevator-car in such manner as to preclude the operation of such car until after the closing of the door. 15 Its purpose is to preclude accidents due to the hoistway-doors being open while the elevator-car is in operation.

The invention is illustrated in the accompanying drawings, in which—

20 Figure 1 is a vertical section of a hoistway provided with sliding doors and an elevator-car operating in such hoistway. Fig. 2 is a similar view showing the invention as applied to an elevator operating in a hoistway 25 equipped with hinged or swinging doors. Fig. 3 is a horizontal section illustrating, on an enlarged scale, the mechanism shown in Fig. 1. Fig. 4 is a similar view showing, on an enlarged scale, the mechanism shown in Fig. 2.

30 Referring to the drawings, in which similar letters of reference denote corresponding parts, A designates a hoistway. This may be of any desired construction and equipped with doors of any suitable character. I have. 35 illustrated herein doors A', having a sliding movement, Figs. 1 and 3, and doors A², having a hinged or swinging movement, Figs. 2 and 4. Doors of the former character are commonly provided with ways or tracks a.

40 B designates the elevator-car, having the doorway b and consisting generally of the bottom b', sides b², back b³, and front b⁴, in the latter of which the doorway b is formed. The bottom b' is provided with the usual perforation b⁶, through which passes the starting and stopping rope b⁵.

45 CC designate arms, one end of each of which is keyed or otherwise secured to the rocking shaft or pivot c. The upper end of pivot c is mounted in a fixed bearing c', its lower end

projecting through a perforation c² in the car-bottom b'. Beneath the car-bottom the pivot c is rigidly secured to one end of the arm D. The arms C C, with the arm D, form as a whole a bell-crank lever.

55 Pivoted in the free ends of the arms C C is a roller E, capable of revolution in its bearings. With this roller E coacts, in the case of the apparatus shown in Figs. 1 and 3, a bar e, projecting inwardly from the inner side 60 of the sliding door A'. The end of the bar e which first comes into contact with the roller is beveled at e', as shown in Fig. 3.

F designates a lever fulcrumed at f to the under side of the car-bottom b'. The free end 65 of this lever is provided with a clutch for grasping and securely holding the starting and stopping rope b⁵ when said lever is moved to the proper position for that purpose. In the present instance I have shown a conventional clutch mechanism consisting of a block f', secured to the under side of the car-bottom adjacent to the rope b⁵, said block being provided with a jaw f². The free end of the lever is provided at a point also adjacent to 70 the starting and stopping rope b⁵ with a similar jaw f³. As will be readily seen, the movement of the lever F upon its fulcrum serves to release or grip (according to the direction of the movement) the rope b⁵.

75 G designates a connection between the arm D and lever F. This connection is here shown as consisting of two rods joined by a turnbuckle g. The function of said turnbuckle is to take up slack and generally to 80 provide for the proper adjustment of the parts.

85 The operation of the structure shown in Figs. 1 and 3 is as follows: The hoistway-doors in this embodiment of the invention are of the sliding variety. When the car reaches 90 the floor, the door A' is opened by sliding the same toward the left in the ways. During this movement the bar e is brought into contact with the roller E, (first at the beveled end of said bar,) whereby the roller is pressed 95 inwardly toward the interior of the car. This movement operates the bell-crank mechanism, consisting of arms C C and D, throwing the end of the rod D distant from the pivot c to the left and by means of the 100

connecting-rod G causing a corresponding movement of that end of the lever F to which the rod G is attached, whereby the clutch mechanism is brought into operative relation 5 to the starting and stopping rope, so as to grip the same and thereby preclude its movement while the door A' remains in open position. Before the rope b⁵ can be operated it is necessary to close the door A'. In doing 10 this such door is moved to the right, and when it has passed beyond the roller E the latter resumes its normal position (that shown in Fig. 3) by reason of the tension exerted by spring d⁵. This causes a corresponding movement 15 of the arms C and D and rod G, and the lever F releases the clutch mechanism and permits the starting and stopping rope to be operated.

Turning now to the structure illustrated in 20 Figs. 2 and 4, it will be seen that the construction of the safety device is the same as that heretofore described, with the exception of the means coacting with the door for causing such device to operate. In this instance, as 25 before stated, the door A² is of the hinged variety, conventional hinges being shown at a². The inner or hinged end of the door is provided with a cam H, here shown as operating through the slot h in the door-jamb 30 or hoistway-easing. Normally—that is to say, when the door is in closed position, as 35 shown in Fig. 4—the cam H is out of engage-

ment with the roller E. When the door is opened, however, said cam is brought into contact with said roller, and the latter is 35 pressed inwardly toward the interior of the car, whereupon the same operation takes place as that heretofore described in connection with the structure of Figs. 1 and 3, when the bar e of the sliding door A' presses the 40 roller in the same direction—i. e., the clutch mechanism is operated to firmly grip the starting and stopping rope and preclude the the movement of the car.

What I claim, and desire to secure by Letters Patent, is—

In a safety device for elevators having the operating-rope on the latch side of the hoistway-door, the combination of a car, a bell-crank lever attached thereto, a roller on one 50 end of said bell-crank lever adapted to roll upon the hoistway-door when said door is moved, a lever upon the opposite side of the car, said lever having a clutch for the operating-rope at one end thereof, and an adjustable 55 connection between the ends of said levers, substantially as set forth.

This specification signed and witnessed this 18th day of May, 1897.

WALTER E. BENNETT.
